United States Patent

Des. 239,908
Patented May 18, 1976

239,908

SPOON OR SIMILAR ARTICLE

Ellen B. Manderfield, Syracuse, N.Y., assignor to Oneida Ltd., Oneida, N.Y.

Filed May 28, 1974, Ser. No. 474,043

Term of patent 14 years

Int. Cl. D7—03

U.S. Cl. D7—137

FIG. 1 is a front view of a spoon showing my new design;

FIG. 2 is a rear view thereof;

FIG. 3 is a side view thereof, the undisclosed side being substantially identical with the side shown in FIG. 3;

FIG. 4 is an enlarged cross-section taken on line 4—4 of FIG. 6;

FIG. 5 is an enlarged cross-section taken on line 5—5 of FIG. 1; and

FIG. 6 is an enlarged front view of the decorated portion of the handle of the spoon shown in FIG. 1.

I claim:

The ornamental design for a spoon or similar article, substantially as shown and described.
